HOLDER FOR A HAIR CURLING IRON

Thomas M. West III, 206 W. Alton Ave.,
Santa Ana, Calif. 92707

Filed Aug. 25, 1975, Ser. No. 607,561

Term of patent 14 years

Int. Cl. D6—04

U.S. Cl. D6—125

FIG. 1

FIG. 4

FIG. 2

FIG. 5

FIG. 3

FIG. 6

FIG. 1 is a perspective view of a holder for a hair curling iron showing my new design;

FIG. 2 is a front elevational view thereof;

FIG. 3 is a bottom plan view thereof;

FIG. 4 is a top plan view thereof;

FIG. 5 is right side elevational view, the left side elevational view being a mirror image thereof; and

FIG. 6 is a rear elevational view thereof.

I claim:

The ornamental design for a holder for a hair curling iron, as shown and described.
